RATION OF NEW JERSEY.

WORK-SUPPORT.

1,032,881.

Specification of Letters Patent. Patented July 16, 1912.

Application filed February 20, 1911. Serial No. 609,626.

To all whom it may concern:

Be it known that we, ALFRED CHAPLIN and JOSEPH J. MARSH, subjects of the King of England, residing at Leicester, Leicestershire, England, have invented certain Improvements in Work-Supports, of which the following description, in connection with the accompanying drawings, is a specification, like reference characters on the drawings indicating like parts in the several figures.

This invention relates to work supports and is herein shown as embodied in a work support which is especially adapted for use with machines for inserting nails, slugs or other fastenings into the heels or soles of boots or shoes. It will be understood, however, that many features of the invention may be embodied to advantage in work supports of other types.

Boots and shoes are slugged or nailed both "on the last" and "off the last," the last being usually supported, in the one case, by a jack and the shoe being usually supported, in the other case, by a horn. When firm localized support is desired at the point where the nail or other fastening is to be inserted, a horn is preferably employed, particularly if the nails are to be clenched upon the inside of the shoe, as for example when "nailing on" the outsole. In either case, however, when ordinary work supports are employed, the sole or heel of the shoe is only supported against those operations which are performed upon parts thereof lying over the interior of the shoe. The projecting margin of the sole, in such cases, is unsupported, and if, as in quilting or loading operations, it is desired to insert slugs or other protectors close to or even in this margin, difficulty is usually encountered in properly performing the inserting operation, and moreover there is danger of breaking down the margin.

An object of the invention is to improve the construction of work supports by providing convenient and efficient means for supporting the projecting margin of a shoe sole.

In particular, the invention is designed to afford a better support for a boot or shoe, while the nails or the like are being driven therein close to the edge of the sole. For this purpose, according to this invention, an auxiliary support is provided, in addi-

tion to the usual horn or other support which is located within the boot or shoe, the auxiliary support being adapted to engage and support the projecting margin of the sole of the boot or shoe, and, for this purpose, preferably to enter within the crease between the margin and the upper. The inside support and the outside support, which may be sometimes hereinafter referred to as the "welt support," may be relatively adjustable in a direction toward and away from the surface of the work so as to compensate for differences in thickness or for irregularities of the surface in the parts of the work engaged by the said supports respectively. This is a very important practical feature of the invention.

Another important feature of the invention is the arrangement of the parts whereby the above-mentioned relative adjustment of the supports is effected automatically. To this end in the preferred embodiment of the invention an equalizing device is so arranged that a constant proportion of the total pressure shall be applied by the horn and the welt support respectively, notwithstanding the variations in thickness of succeeding soles at the points where the work is supported.

As above suggested an important object of the invention is to provide a work support which will afford a proper support for the shoe when operations are being performed upon the sole close to the edge thereof.

In order that the work support may be adjusted to bring its supporting surface into such relation to the path of movement of the shoe past the operating mechanism that the operations may be performed at the desired distance from the sole edge, another feature of the invention is the provision of novel and convenient means for effecting a relative adjustment of the working surface of the horn or other work support with respect to the point at which the operation is performed upon the shoe, so that the operation may be performed closer to or farther from the edge of the work, as desired. In order further to insure the proper support of the work for operations close to the edge thereof, means is preferably provided for pressing the welt support into the crease of the shoe. This last named means may comprise a yielding device that will maintain the support in the crease but will yield.

when required either by the nature of the work being acted upon or by the width of the material between the horn and the welt support.

5 Another feature of the invention is the provision of means for effecting an automatic separation of the inside and outside supports when the work support is moved into work receiving position, thereby, in the 10 illustrated embodiment of the invention, leaving free access to the horn for the removal of the shoe and for placing another shoe upon the horn.

The invention also contemplates the provision of means for holding the welt support in an inoperative position when it is not required by the nature of the work or by the location of the work with respect to the mechanism which operates thereon.

20 Other features and objects of the invention will be apparent when the following description and claims are considered in connection with the accompanying drawings, in which,—

25 Figure 1 is a side elevation of a portion of a nailing machine, showing the invention applied thereto; Fig. 2 is a view similar to a portion of Fig. 1, but showing the parts in a different operative relationship, some 30 parts being shown in section, and Fig. 3 is a plan of a part of the machine illustrated in Figs. 1 and 2, this view illustrating especially the means for adjusting the horn in and out with respect to the machine.

35 The work support shown in the drawings comprises a horn 2, of substantially usual construction, the horn 2 being adapted to enter the boot or shoe and to support at the point of operation the sole upon which the 40 machine is operating. As is usual in this type of machines, the horn is caused to clamp the work against a work abutment 4, surrounding the point of operation, by means of a spring, not herein shown, or by 45 connections with a cam upon the main shaft, also not shown.

The horn 2 is clamped in a bracket 6 which has a hub 8 rotatable about an eccentric bushing 10 which is mounted upon the 50 horn shaft or post 12. A sleeve 14 is mounted upon the post 12 below the bushing 10 and is provided with a flange 16 which supports the bushing 10 and the hub 8 of the bracket 6. The sleeve 14 and the bushing 55 10 are arranged to slide upon the post 12 to an extent limited by the pin and slot connection hereinafter described. By turning the eccentric bushing 10 the bracket 6 and with it the horn 2 may be adjusted in and 60 out with respect to the machine. To maintain the bushing 10 in its adjusted position, any convenient locking or retaining device may be employed, that herein illustrated comprising a spring-pressed plunger 18 arranged in a recess 20 in the horn post, said

plunger having a cone-shaped end that is adapted to engage one or another of a series of grooves in the inner surface of the bushing 10.

Upon a pin or stud 22 secured to the horn post 12 is fulcrumed an equalizing lever 24 which at one end is pivotally connected to an arm 26 that carries the welt support 28, shaped to fit into the crease of the boot or shoe and thus afford a support for the margin or edge of the sole. The other end of the equalizing lever 24 is pivotally connected to a bracket or extension 30 of the sleeve 14 hereinabove referred to. The sleeve 14 is provided with a clearance slot 32, through which the pin or stud 22 extends. This slot permits a relative movement of the sleeve 14 and the horn post 12, so that when the horn 2 is either raised or lowered relatively to the welt support the sleeve 14 will be correspondingly moved, and by reason of its connections with the equalizing lever 24 will effect a movement of the welt support 28 in a direction opposite to that in which the horn 2 is moved. 85 The connection between the equalizing lever 24 and the bracket 30 is such as to permit of a lateral movement of the end of the lever 24 to compensate for the arcual movement of this end of the lever when turning on the pin 22. This connection may comprise a block 34 arranged to slide in a slot 36 in the bracket 30.

90 The welt support 28 is adjustably secured to the arm 26, said support being provided with a shank 38 which enters a bore in the arm 26. The bore in the arm 26 is provided with a split wall and a clamping screw 40. To cause the welt support 28 to be kept in the crease of the shoe, the arm 26 is drawn 95 normally toward the horn by a spring 42 which at one end is secured to the arm 26 and at its other end to the bracket 30.

100 At times it may be desirable to use the horn without the welt support, as for example, when operating upon parts of the sole remote from the edge. Provision is therefore made for holding the welt support out of operative relation to the horn at such times. In the illustrated construction a link 110 or catch 44 is provided for this purpose, the catch 44 being pivoted upon the pin or stud 22 and being provided with a hook-shaped end adapted to hook over a pin 46 upon a downward extension 48 of the arm 26. This 115 downward extension of the arm 26 has a further purpose which will now be set forth.

120 In the machine herein illustrated, as is customary with this type of machines, provision is made for lowering the work support into work receiving position. When the work support is moved into work clamping position by a spring, a treadle is usually provided for depressing the work support against the tension of its spring. To facilitate

tate the removal of the work from the work support when in work receiving position, and also to facilitate the placing of another piece of work upon the work support, a feature of the invention consists in the provision of means for automatically separating the horn and welt support as the horn is moved into work receiving position. To this end, in the illustrated construction, the downward extension 48 of the arm 26 is provided with a bowl or runner 50 which is adapted to engage a cam track 52 upon a bracket 54 adjustably confined upon the frame 56 of the machine by set screws 58 entering a slot 60 in said bracket.

When the horn 2 is lowered into its work receiving position, the welt support 28 by reason of its connections with the horn post 12 will also be lowered and the runner 50 will engage the cam track 52 upon the bracket 54. Continued depression of the horn 2 will cause the runner 50 to travel along the cam track, thus causing the arm 26 to turn about its pivotal connection 62 with the lever 24 into the dotted line position shown in Fig. 1. This leaves unobstructed access to the horn for removal of the work or for placing new work upon it.

The operation of the machine so far as the present invention is concerned will no doubt be understood from the foregoing description, but it may be briefly restated as follows: When the horn post 12 is raised to bring the work into position to be operated upon, the pin or stud 22 secured to said post will carry upward the equalizing lever 24 and with it the welt support 28 and the horn 2 until these parts bring the work into contact with the work abutment 4 on the machine. If the horn 2 and the welt support 28 are in engagement with the respective portions of the work above them at the time the upper surface of the work comes into contact with the work abutment, no relative movement of these parts will take place. If, however, only one of these parts is in engagement with the work at the time the work abutment is engaged by the upper surface of the work, the part that is in contact with the work will have its upward motion arrested by the engagement of the work by the work abutment, and the further movement of the horn post 12 will then cause the equalizing lever 24 to be turned on its pin or stud 22, thus moving into engagement with the under side of the work that one of the two parts or supports which was not in engagement with the work at the time the work abutment was engaged by the upper surface of the work. The upward movement of the horn post 12 will continue until each of the two supports brings to bear upon the work the determined proportion of clamping pressure which has been allotted to it by reason of the relative lengths of the arms of

the equalizing lever 24. For example, let it be assumed that the two supports are level and that the part of the work engaged by the horn 2 is of greater thickness than the part engaged by the welt support 28. In this case, in the upward movement of the post 12 the portion of the work above the horn will first contact with the work abutment and the further movement of the horn will thus be prevented. The post 12 will, however, continue to move upward and through the pin or stud 22 carried by it will turn the equalizing lever 24 so that the welt support 28 will continue to move upward until it clamps the part of the work engaged by it against the work abutment with a pressure which bears a definite proportional relation to that exerted by the horn. The action will be reversed if the thicker part of the work is above the welt support. If desired, the machine may be adapted to deal with any class of work by changing the proportional relation of the two arms of the equalizing lever.

By adjusting the eccentric bushing 10, the working surface of the horn 2 may be moved toward or away from the path in which the nails are driven for the purpose of varying the position in the shoe in which the nails are inserted. As the arm 26 which carries the welt support is drawn toward the horn by the spring 42, the welt support 28 will always be maintained in the crease between the upper and the welt, or between the upper and the projecting margin of the sole, and yet will be allowed to move outwardly if an increased width of material should come between the horn and the welt support.

It will be noted that the relative adjustment of the horn and the margin supporting means to accommodate variations in the thickness of the material interposed between them, as well as the relative adjustment of these parts to accommodate differences in the thicknesses of the respective parts of the shoe interposed between them and the work abutment, is effected automatically, both of these adjustments taking place during the movement of the work support from work receiving position to work clamping position.

Having described our invention, what we claim as new and desire to secure by Letters Patent of the United States is:—

1. In a machine of the class described, means for supporting a shoe sole upon the inside of the shoe, means for supporting the projecting margin of the sole upon the outside of the shoe, and equalizing means connecting said outside and inside supporting means in such manner as to permit free relative movement of adjustment of said supports.

2. In a machine for operating upon soles,

- means for supporting the sole of a shoe close to the inside face of the upper, means for supporting the adjacent marginal portion of the sole close to the outside face of the upper, each of said supporting means being adapted to support the sole against the force of the operations thereon, and means for yieldingly maintaining said two supporting means in coöperative relation to each other.
3. In a machine of the class described, means for supporting a shoe sole upon the inside of a shoe, means for supporting the projecting margin of said sole, and connections between said inside and outside supporting means constructed to cause an automatic relative adjustment of said means to different relative thicknesses of the sole parts supported.
4. In a machine of the class described, means operating inside the shoe to support the shoe sole, means operating outside the shoe to support the projecting margin of the sole, a single means for moving said two supporting means into and out of operative supporting position, and means connecting said last mentioned means and the supporting means for adjusting said supporting means automatically to varying inside and outside sole thicknesses.
5. In a machine of the class described provided with a work abutment, means operating inside the shoe to clamp the portion of the sole to be operated upon against the work abutment, means operating outside the shoe to clamp the adjacent portion of the sole margin against the work abutment, and equalizing means constructed to maintain a fixed ratio of clamping pressures between the two clamping means for varying sole thicknesses.
6. In a machine for operating upon soles, a horn, margin supporting means shaped to enter the crease between the upper and the sole margin to support the margin against the force of the operations thereon, and automatic means for maintaining said horn and margin engaging means in coöperative relation to each other.
7. In a machine for operating upon soles, a horn, and means for supporting the margin of a shoe sole adjacent to the part supported by the horn against the force of the operations upon the sole, yieldingly maintained in coöperative relation to said horn.
8. In a machine of the class described, a horn, means for supporting the projecting margin of the sole adjacent to the portion supported by said horn, and equalizing connections between said horn and said margin supporting means arranged to permit free relative movement of adjustment of said horn and said supporting means.
9. In a machine of the class described, a work support comprising separate means for bringing clamping pressure to bear upon different parts of a shoe, a single means for transmitting the clamping pressure to said clamping means, and means interposed between said single means and said clamping means for causing the clamping pressures transmitted to the shoe to bear a definite proportional relation to each other for varying relative thicknesses of the parts clamped.
10. In a machine of the class described, provided with a work abutment, a horn, means for causing said horn to clamp the sole of a shoe against the work abutment, margin supporting means also operated from said aforementioned means to clamp the projecting margin of a sole against said work abutment, said margin supporting means being shaped to enter the crease between the upper and the sole margin, and means connecting said margin supporting means and said horn constructed to effect such relative adjustment of the connected parts during the work clamping movement that the pressures upon the respective parts of the sole supported by said horn and said margin supporting means bear a determined proportional relation to each other.
11. In a machine of the class described having a work abutment against which the work is clamped, a horn, margin supporting means, and means for bringing to bear upon the respective parts of the sole which are clamped between the work abutment upon one side and the horn and the margin supporting means upon the other side pressures which in amount bear a determined relation to each other for varying relative thicknesses of the parts clamped.
12. In a machine for operating upon soles, a work support movable between a work receiving position and a work clamping position, said work support comprising inside and outside shoe sole supporting means arranged to support the sole against the force of the operations thereon, and means for automatically effecting a relative adjustment toward each other of said inside and outside means as the work support is moved into work clamping position.
13. In a machine of the class described, means for supporting upon the inside of the shoe the part of the sole to be operated upon, means for supporting upon the outside of the shoe the adjacent portion of the sole margin, a single means for moving said two supporting means into and out of operative supporting position and means for effecting automatically both a relative lateral adjustment of said means and a relative vertical adjustment of said means to suit the conditions of the work to be operated upon.
14. In a machine for operating upon soles, a work support movable between a work receiving position and a work clamping position, said work support comprising inside

- and outside shoe sole supporting means maintained normally in coöperative relation to each other and adapted to support the sole against the force of the operations 5 thereon, and means for automatically separating said supporting means as the work support is moved into work receiving position.
15. In a machine for operating upon soles, 10 means for supporting the sole of a shoe upon the inside, means for supporting the projecting margin of said sole yieldingly pressed toward said inside supporting means, means for moving said supporting means 15 into and out of supporting position, and means for positively separating said supporting means as they are moved out of operative supporting position.
16. In a machine for operating upon soles, 20 a horn and margin supporting means maintained yieldingly in coöperative relation to said horn whereby said horn acts inside the shoe to support the sole against the operations thereon and the margin supporting 25 means acts outside the shoe for the same purpose, means for raising and lowering said horn and margin supporting means, and means for moving said margin supporting means out of coöperative relation to said 30 horn when the horn is lowered.
17. In a machine of the class described, a horn, sole margin supporting means yieldingly maintained in coöperative relation to said horn whereby said horn acts inside the 35 shoe to support the sole against the operations thereon and the margin supporting means acts outside the shoe for the same purpose, and means for locking said margin supporting means out of operative relation 40 to said horn.
18. In a machine for operating upon soles, a vertically movable horn and vertically 45 movable sole margin supporting means, said horn and sole margin supporting means being adapted to support the sole against the force of the operations thereon and being relatively self-adjustable along the paths of their vertical movements.
19. In a machine for operating upon soles, 50 a vertically movable horn and vertically movable sole margin supporting means, said horn and sole margin supporting means being adapted to support the sole against the force of the operations thereon and being self-adjustable toward and away from each 55 other.
20. In a machine for operating upon soles, 60 a vertically movable horn and vertically movable sole margin supporting means, said horn and sole margin supporting means being adapted to support the sole against the force of the operations thereon and being arranged for work accommodating relative movement toward, and away from each 65 other.
21. In a machine for operating upon soles, 70 a horn and sole margin supporting means vertically movable into and out of work supporting position, said horn and sole margin supporting means being adapted to support the sole against the force of the operations thereon and being relatively movable along 75 the paths of their vertical movements and during such movements to cause them to come into work accommodating relation to each other.
22. In a machine of the class described having a work abutment, a horn and sole margin supporting means coöperating with said work abutment to clamp a shoe sole in 80 position to be operated upon, said horn and margin supporting means being adapted to support the sole against the force of the operations thereon and being relatively self-adjustable in the direction of their clamping 85 movements to accommodate varying thicknesses of the sole parts clamped.
- In testimony whereof we have signed our names to this specification in the presence of two subscribing witnesses.
